UNITED STATES PATENT OFFICE.

JACOB EMIG, OF BUFFALO, NEW YORK, ASSIGNOR OF ONE-HALF TO JOHN B. PORTER, OF BUFFALO, NEW YORK.

MEAT-CHOPPER.

SPECIFICATION forming part of Letters Patent No. 694,951, dated March 11, 1902.

Application filed February 20, 1901. Serial No. 48,036. (No model.)

To all whom it may concern:

Be it known that I, JACOB EMIG, a citizen of the United States, residing at Buffalo, in the county of Erie and State of New York, have 5 invented new and useful Improvements in Meat-Chopping Machines, of which the following specification, taken in connection with the accompanying explanatory drawings, will fully and clearly disclose the invention, so as 10 to enable others skilled in the art to which it pertains to make and use the same.

This invention relates to that class of meat-chopping machines in which a horizontally-revolving chopping-block is used in conjunction with vertically-movable chopping-knives; and it has for its object the production of a practical, durable, and effective device particularly applicable for kitchen use and also to improve the mechanical construction, arrangement, and combination of the several parts; and to this end it consists in the detail construction and arrangement of the parts, all as hereinafter more fully described, and pointed out in the claim.

25 In the drawings, Figure 1 is a front elevation of my improved meat-chopping machine. Fig. 2 is a vertical section taken on line 2 2, Fig. 1. Fig. 3 is a vertical section taken on line 3 3, Fig. 1. Fig. 4 is a horizontal section 30 taken on line 4 4, Fig. 3. Fig. 5 is a horizontal section, on an enlarged scale, taken on line 5 5, Fig. 1. Fig. 6 is a horizontal section, on a still further enlarged scale, taken on line 6 6, Fig. 1.

35 Referring now to the drawings in detail, like letters of reference refer to like parts in the several figures.

The letter A represents the stationary table, which is supported by standards B, connected together at their lower ends by a bed-plate C, which latter is secured to a base D, constructed of wood or any other suitable material. Said table, standards, and bed-plate constitute the framework of the machine and 45 support the operating mechanism.

E designates a revoluble table having two concentric bearing-ribs e formed on its under side, which are smoothly finished or machined and which coact with two concentric bearing-ribs a, formed on the upper face of the

stationary table, said bearing-ribs also being machined to make a perfect bearing between the stationary table A and the revoluble table E. Oil-ducts e' are formed in the table E, through which oil is passed to lubricate 55 the machined faces of the bearing-ribs, and thereby reduce friction. A bushing F is passed through the stationary table A and is screwed into the revoluble table E to turn with the same, it being provided with an annular flange, which bears against the under side of the stationary table and holds the revoluble table in position on the same. This bushing serves as a guide for the vertically-reciprocating rod, as will presently appear, and when worn can be unscrewed and replaced by another bushing. By this construction a perfect-fitting guide can always be had at a slight cost and without replacing other parts of the machine and a perfect vertical movement given to the knives without lateral sway, thus assuring even contact of the chopping-knives with the chopping-block at every point of their cutting edge.

G designates the chopping-block, and G' 75 the curb or casing, secured thereto by means of screws g or in any other suitable manner. This curb or casing extends below the lower surface of the chopping-block and has inverted-L-shaped slots H formed therein at 80 diametrically opposite points, which receive pins H', projecting from the sides of the revoluble table at points coinciding with the position of the slots H. It is therefore apparent that the chopping-block and its curb or 85 casing can be readily disconnected from the revoluble table to facilitate cleansing.

To the operating-shaft I, which is journaled in the framework, the fly-wheel J is secured, the latter being equipped with a handle J', 90 whereby the machine is operated. The gear-wheel K is secured to the shaft I and meshes with a pinion K', secured to an auxiliary or counter-shaft L, also journaled in the framework below the operating-shaft I. This shaft 95 has a grooved cam M secured thereto, which operates a cam-lever M', pivotally held on the operating-shaft I and which is equipped at its upper end with a pawl m, pivotally secured thereto and adapted to engage the ratchet- 100

teeth e' , formed on the upper face of the revoluble table at its circumferential edge. A spring M^2 is secured at one end to the lower end of the cam-lever M' and at its other end 5 to the base D , its purpose being to keep the lower end of said cam-lever against the cam and cause the pawl secured to its upper end to ride back over the ratchet-teeth, the cam giving the pawl m its stride or push to revolve 10 the table. On revolving the counter-shaft the cam is revolved also and causes the cam-lever to oscillate on the operating-shaft, which causes the pawl m to engage the ratchet-teeth and intermittently revolve the chopping-block, which is secured to the revoluble table. 15

N designates a vertically-reciprocating rod which passes through a guide N' , formed on the framework, and n designates a guide pin or screw which is screwed into the guide to enter 20 the longitudinal groove N^2 , formed in the rod N , the purpose of said groove being to prevent the turning of the rod. This rod passes up through the bushing F , which guides the same, and also through a tube o , secured in an aperture formed centrally in the chopping-block. 25 The tube o serves as a curb to prevent particles of meat from passing down through said aperture. The upper end of the reciprocating rod is reduced in diameter and carries a cross-head P , secured thereto by a thumb-nut P' . To this cross-head vertically-adjustable chopping-knives R are secured, the adjustment of the same to the chopping-block being effected by the vertical adjusting-screws r , which pass through the cross-head and bear against the upper edge of the knives, which latter are held in their adjusted 30 position by the horizontally-disposed binding-screws r' , passing through the cross-head, and

the vertical slots r^2 , formed in said chopping-knives. 40

To the end of the counter-shaft L a crank S is secured, which is pivotally connected by a crank-pin s to a pitman T , also pivotally connected at its opposite end to an adjustable collar T' , secured to the reciprocating rod N by a set-screw V . The chopping-knives may be adjusted to the chopping-block by raising or lowering the collar T' on the reciprocating rod, as the case may require; but 45 for a fine adjustment, which may be necessary when the chopping-block or the edges of the knives are worn uneven, the adjusting-screws r must be resorted to. 50

Having thus described my invention, what 55 I claim is—

In a meat-chopping machine, the combination with the framework, of a stationary table secured thereto, a revoluble table supported on said stationary table, a bushing passing 60 through said stationary table and having a flange bearing against the under side of the same, said bushing entering the revoluble table and being held therein by a screw-threaded connection, a chopping-block secured to said 65 revoluble table, a reciprocating rod guided in said bushing, chopping-knives carried on said rod, and mechanism for operating said rod and revolving said revoluble table, substantially as set forth. 7c

In testimony whereof I have hereunto set my hand in the presence of two subscribing witnesses.

JACOB EMIG.
